UNITED STATES PATENT OFFICE.

FRANK C. HINCKLEY, OF STRATFORD, CONNECTICUT, ASSIGNOR TO DICTAPHONE CORPORATION, OF BRIDGEPORT, CONNECTICUT, A CORPORATION OF NEW YORK.

DESIGN FOR A CASING FOR A DICTATING MACHINE OR SIMILAR ARTICLE.

Application filed March 6, 1924. Serial No. 8,855. Term of patent 14 years.

To all whom it may concern:

Be it known that I, FRANK C. HINCKLEY, a citizen of the United States, residing at Stratford, in the county of Fairfield and State of Connecticut, have invented a new, original, and ornamental Design for a Casing for a Dictating Machine or Similar Article, of which the following is a specification, reference being had to the accompanying drawing, forming part thereof.

Figure 1 is a perspective view of the dic-

tating machine casing, showing my new design.

Fig. 2 is a side elevation of the casing looking at it from the right.

Fig. 3 is a side elevation of the casing looking at it from the left.

I claim:

The ornamental design for a casing for a dictating machine or similar article, as shown.

FRANK C. HINCKLEY.
